INVENTOR.

UNITED STATES PATENT OFFICE.

GEORGE N. LEMMON, OF GREENSBURG, PENNSYLVANIA.

ELECTRIC SWITCH.

1,219,470.

Specification of Letters Patent. Patented Mar. 20, 1917.

Application filed February 1, 1915. Serial No. 5,561.

To all whom it may concern:

Be it known that I, GEORGE N. LEMMON, a citizen of the United States, residing at Greensburg, in the county of Westmoreland and State of Pennsylvania, have invented a new and useful Electric Switch, of which the following is a specification.

My invention relates to a switch for controlling electric currents and its object is to provide a simple and effective means of securing contact between a solid metal surface and a metallic flexible brush opposed thereto.

The priority of Letters Patent issued to A. W. Burke # 1,099,421 is acknowledged, and all claims are made subject to the claims granted therein.

On the attached drawing, Figure 1 shows a side view of a switch embodying my invention. Fig. 2 shows a top view of the conducting members of the switch with the contact-making parts not quite in contact. Fig. 3 shows a top view of the conducting members fully in contact with the switch closed.

A switch embodying my invention is shown in Fig. 1 of the attached drawing. The base, *a*, carries a movable support, *b*. Insulators, *c*, *c*, *c'*, are supported on these members and in turn support the conducting parts above. The movable member, *d*, carries a contact-member, *e*, which has a contact surface, *g*, and interlocking parts, *m*, *m*, and which is pivotally attached to the movable member, *d*, by the joint, *n*. The member *e* is limited in its motion about the pivot between the two positions shown in Figs. 2 and 3. This may be done by stops, *p*, *p*, or by other means. A spring, *s*, keeps *e* normally in the position shown in Fig. 2. The stationary conducting member, *f*, carries a flexible contact brush, *h*, and interlocking parts, *k*.

The operation is as follows:-

As the switch, *b*, closes, the interlocking parts, *m*, *m*, engage with the part, *k*; as shown in Fig. 2; further motion produces pivotal motion of the contact member, *e*, about the pivot, *n*; the surface, *g*, approaches and comes into forcible contact with the brush, *h*; and the parts *m*, *m*, become interlocked with the part, *k*, as shown

in Fig. 3. An essential part of the operation is the toggle-joint action which is secured by the motion of the part *e* about its pivot, *n*, thereby bringing *e* into approximate alinement with the member *d* and producing heavy pressure between the parts *g* and *h*, with relatively small rotative effort applied to the member *b*. When the switch is opened the parts *m*, *m*, remain interlocked with the stationary part, *k*, until the contact member, *e*, has partially moved about its pivot, *n*, and the contact surface, *g*, has become released from its contact with the brush, *h*.

The essential feature of my invention is the pivotal action of the member, *e*, which thereby produces forcible contact between the surface, *g*, and the brush, *h*, and interlocks the parts, *m*, *m*, *k*. The brush, *h*, and the surface, *g*, may be interchanged with one another; also the member, *e*, may be pivotally mounted on, *f*, and the members, *k*, *k*, be mounted on the member, *d*, and such modifications do not change the essential features of my invention.

I claim:

1. An electric switch having in combination a stationary insulated support, a rotative insulated support, a conducting member mounted on each of these supports, a flexible contact-making brush, mounted on one of these conducting members, and a contact-making member pivotally mounted on the other conducting member and extending as a continuation of the conducting member upon which it is mounted, toward the other conducting member.

2. An electric switch having in combination a stationary insulating contact-supporting member, a rotative insulating contact-supporting member, and a contact member pivotally mounted on one of these supports and capable of limited motion about its pivot and of securing toggle-joint action in combination with a contact member on the other support.

3. In an electric switch, a pair of coöperating contact members, two pivoted levers arranged to form a toggle-lever, one of said contact members being carried by one of said pivoted levers, and coöperating inter-

locking members, one connected to each contact member.

4. In an electric switch, a fixed contact member, a movable contact member, a pair
5 of pivoted levers forming a toggle, one of said levers carrying said movable contact

member, and coöperating interlocking members, one connected to each contact member.

G. N. LEMMON.
